US00D716748S

(12) **United States Design Patent**
Wang

(10) **Patent No.:** **US D716,748 S**
(45) **Date of Patent:** ** *Nov. 4, 2014

(54) **HANDSET**

(71) Applicant: **Nokia Corporation**, Espoo (FI)

(72) Inventor: **Jing Wang**, Beijing (CN)

(73) Assignee: **Nokia Corporation**, Espoo (FI)

(*) Notice: This patent is subject to a terminal disclaimer.

(**) Term: **14 Years**

(21) Appl. No.: **29/446,573**

(22) Filed: **Feb. 25, 2013**

(51) LOC (10) Cl. **14-03**

(52) U.S. Cl.

USPC ..... **D14/138 G**

(58) **Field of Classification Search**

(57) **CLAIM**

The ornamental design for a handset, as shown and described.

DESCRIPTION

FIG. 1 is a perspective view of a handset showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of a handset showing my new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines of the handset in each embodiment, and the unshaded regions within the broken lines, form no part of the embodiment in which they are shown.

1 Claim, 6 Drawing Sheets
